UNITED STATES PATENT OFFICE

GEORGE W. VEALE, OF CLEVELAND HEIGHTS, OHIO, ASSIGNOR TO THE EATON MANUFACTURING COMPANY, OF CLEVELAND, OHIO, A CORPORATION OF OHIO

POLISHING MACHINE

Application filed August 22, 1927. Serial No. 214,536.

This invention relates to improvements in machines for polishing bumper bars of the type employed at each side of the rear of an automobile, and is of special utility where the bars acted upon have their impact surfaces 5 grooved.

In such machines as constituted previous to my invention, the polishing wheels become worn quickly by the ribs on the bars between the grooves, and frequent removal of 10 the wheels and substitutions of newly surfaced ones are required.

One of the objects of my invention is the provision of means which will permit the polishing 15 of grooved bars with an even wear upon the abrading surface of the polishing wheel.

A more specific object is the provision of means for imparting motion to the bar holder at right angles to the plane of the polishing wheel, and more especially for imparting a 20 plurality of reciprocations for each revolution of the holder.

Other objects and features of novelty will appear as I proceed with the description of 25 that embodiment of the invention which, for the purposes of the present application, I have illustrated in the accompanying drawing, in which:

Fig. 1 is a side elevational view of a machine embodying my invention;

Fig. 2 is an end elevational view of the work supporting rack showing the relation between the polishing wheels and the bumper bars in position on the rack; and

Fig. 3 is a fragmental sectional view taken substantially on the line 3—3 Fig. 2.

The machine as illustrated herein comprises a pair of supporting beams 10 to which are bolted standards 11 and 11' supporting bearings for a shaft 12, these bearings being so constituted as to permit longitudinal movement of the shaft therethrough. Shaft 12 carries a work supporting rack which includes two circular side plates 13 and 13', the hubs of which are pinned as at 14 to the shaft.

These plates are joined near their peripheries by a series of fixed rods 15 and 16 and rotatable rods 17. The rods 15 and 16 each 50 have two sets of collars 18, assuming that the

machine is built for two polishing wheels, as herein illustrated, which collars are adapted to properly align the bars 19 to be worked upon. When a pair of bars are to be mounted on the rack or carrier, the handle 20 on rod 17 is swung around so as to direct the pins 21 in that rod backwardly in the general direction of the rods 16 and 15. One end of each bar 19 is then hooked around the rod 15 between the collars 18 thereon and the other end is swung down over the rods 16 and 17 between the collars 18 on the rod 16. Assuming that both bars are in place on a given set of rods, the handle 20 is turned anti-clockwise to bring pins 21 into the hooks of the bumper bars and until the pins are beyond the dead center positions where the resilience of the curved bars 19 holds the pins. The bars are thus locked in position. The reverse procedure is, of course, followed in removing the 70 bars.

The rack is rotated quite slowly by a belt 22 running over a pulley 23 fixed to the shaft 12, the belt being of some little length so that it is not displaced by the lengthwise movement of shaft 12 later to be described. Drive for the belt 22 comes from a small pulley 40 which rotates with a large gear wheel 41 that is driven by a pinion 42 fixed with respect to a pulley 43 that is driven by a belt 44 from a small pulley 45 on a shaft 33 to be referred to again hereinafter. When a pair of polished bars are removed from a set of rods 15, 16, 17 and a pair of unpolished bars put into their places, the machine is 85 caused to resume movement until a pair of bars have traversed the polishing wheels.

At the left end of the rack between plate 13 and standard 11, I employ a cam mechanism adapted to shift the rack to the right, as 90 viewed in Fig. 2. In the form illustrated, an annular cam 24 with a number of high spots is attached to the plate 13 in a position concentric with the shaft 12, being secured to the plate preferably by stud bolts 25. A pair of brackets 26 bolted to the standard 11 carry a roller 27 which bears upon the face of the cam 24. It is, of course, immaterial whether the cam be on the rotating part and the follower on the fixed part or whether 100

their arrangement be reversed. In order to hold the cam 24 up against the follower 27 at all times and to shift the rack to the left as the low spots of the cam come opposite the follower 27, I mount a coil spring 28 upon the shaft 12 between the standard 11' at the right-hand side of the machine and a sleeve 29 which may be either separate from or fastened to the plate 13'.

10 The polishing wheels are shown at 30, being mounted on a shaft 31 which is capable of some vertical movement. This shaft may be rotated by any suitable means, as by a belt 32 driven from a shaft 33 which is in turn driven by a motor 34 or other source of power. The working faces of the wheels 30 are of a breadth sufficient to cover the bars 19 in all positions of the work supporting rack resulting from its transverse movement. I 15 preferably employ a cam with as many high spots on it as there are sets of supporting rods 15, 16, 17, but it is essential only that there be a constant transverse movement of the rack as each pair of bars moves under the polishing wheels.

20 Owing to the fact that the curvature of the bars 19 is different from that of the rack which supports the bars, the polishing wheels 30 must have a slight vertical movement. To this end they are mounted in a frame 46 which is mounted to swing about the shaft 33. The frame 46 is balanced by means of a beam 47 pivoted at 48 to a bracket 49 and pivotally connected at 50 to the frame 46. A 25 proper balance is attained by a weight 51 and an adjustable weight 52.

Having thus described my invention, I claim:

1. In a machine for polishing bumper bars, 30 a rotatable rack, means for supporting the bars upon the periphery of said rack end to end in a plane at right angles to the axis of the rack, means for rotating said rack continuously, a polishing wheel movable radially of said rack and mounted in substantially the same plane and arranged to engage the bars and pass over their surfaces longitudinally as the rack rotates, and means for imparting a plurality of reciprocations to said 35 rack parallel to its axis during each revolution of the rack.

2. In a machine for polishing bumper bars, a rotatable rack, means for supporting the bars upon the periphery of said rack in a 40 plane at right angles to the axis of said rack, means for rotating said rack continuously end to end in a plane at right angles to the axis of the rack, a polishing wheel movable radially of said rack and adapted to contact 45 with the bars and pass over their surfaces longitudinally as the rack rotates, a cam on one side of the rack for imparting axial motion to the rack during its rotation, and a spring upon the opposite side of the rack for 50 returning the same.

3. In a machine for polishing bumper bars, a slowly moving rotatable rack, means for supporting the bars upon the periphery of said rack, in a plane at right angles to the axis of the rack, means for rotating said rack continuously, a polishing wheel movable radially of said rack and adapted to contact with the bars and pass over their surfaces longitudinally as the rack rotates, a cam on one side of the rack having a plurality of high spots for imparting axial motion to the rack during its rotation, and a spring upon the opposite side of the rack for returning the same.

4. In a machine of the character described, the combination of a frame, a rack rotatably carried by said frame, means for supporting the work in an end to end position in a plane at right angles to the axis of the rack, means for continuously rotating said rack, means pivotally carried by said frame and adapted to support a polishing wheel in a position to contact with the work and pass over the surface thereof longitudinally as the rack rotates, a cam on one side of the rack for imparting axial motion to the rack during its rotation, and a spring upon the opposite side of the rack for returning the same.

In testimony whereof, I hereunto affix my signature.

GEORGE W. VEALE.

CERTIFICATE OF CORRECTION.

Patent No. 1,875,962.

September 6, 1932.

GEORGE W. VEALE.

It is hereby certified that the name of the assignee in the above numbered patent was erroneously described and specified as "The Eaton Manufacturing Company", whereas said name should have been described and specified as Eaton Manufacturing Company, as shown by the records of assignments in this office; and that the said Letters Patent should be read with this correction therein that the same may conform to the record of the case in the Patent Office.

Signed and sealed this 22nd day of November, A. D. 1932.

M. J. Moore,
Acting Commissioner of Patents.
